UNITED STATES PATENT OFFICE.

HARRY W. TAUDTE, OF BEAVER FALLS, PENNSYLVANIA, ASSIGNOR TO COOPERATIVE FLINT GLASS CO., OF BEAVER FALLS, PENNSYLVANIA.

DESIGN FOR A SMOKER'S TRAY.

Application filed June 11, 1926. Serial No. 18,006. Term of patent 7 years.

To all whom it may concern:

Be it known that I, HARRY W. TAUDTE, a citizen of the United States, residing at Beaver Falls, in the county of Beaver and State of Pennsylvania, have invented a new, original, and ornamental Design for a Smoker's Tray, of which the following is a specification, reference being had to the accompanying drawing, forming part thereof.

I claim:

The ornamental design for a smoker's tray, as shown.

HARRY W. TAUDTE.
